REVOLVABLE DISPLAY STAND

Joseph F. Bauman, Trenton, N.J., assignor to Emanuel Roth Company, Inc., Secaucus, N.J.

Filed May 4, 1972, Ser. No. 250,466

Term of patent 14 years

Int. Cl. D6—99

U.S. Cl. D6—24

FIG. 1 is a front perspective view of a revolvable display stand, showing my new design;

FIG. 2 is a perspective view of an alternative embodiment of the revolvable display stand of FIG. 1, showing my new design.

It should be understood that the left-hand and rearward sides of the displays of FIGS. 1 and 2 are identical to the right-hand and forward sides shown in the above mentioned figures.

I claim:

The ornamental design for a revolvable display stand, as shown and described.
